SPECIFICATION forming part of Design No. 22,480, dated May 30, 1893.

Application filed February 10, 1893. Serial No. 461,837. Term of patent 3½ years.

To all whom it may concern:

Be it known that I, GEORGE E. HOMER, a citizen of the United States, residing at Boston, in the county of Suffolk, State of Massachusetts, have invented a new and original Design for a Spoon, of which the following is a specification, reference being had to the accompanying drawing, forming part thereof.

The drawing represents my newly designed spoon.

The leading features of my design for a spoon are the representation *a* of Trinity Church, Boston, Massachusetts, upon the bowl of the spoon, and a medallion portrait *b* of Phillips

Brooks upon the handle near its end. The handle between the portrait and the bowl is provided with suitable decoration *c*.

I claim—

The design for a spoon herein shown and described.

In testimony whereof I have signed my name to this specification in the presence of two subscribing witnesses.

GEORGE E. HOMER.
